UNITED STATES PATENT OFFICE.

JOHN HARGREAVES, OF BOLTON, ENGLAND, ASSIGNOR OF ONE-HALF TO NORRIS KAYE, OF HUDDERSFIELD, YORK, ENGLAND.

RING TRAVELER.

1,403,077.

Specification of Letters Patent. Patented Jan. 10, 1922.

Application filed November 10, 1920. Serial No. 423,001.

To all whom it may concern:

Be it known that I, JOHN HARGREAVES, a subject of the King of Great Britain and Ireland, residing at 125 Longfield Road, 5 Bolton, in the county of Lancaster, England, have invented new and useful Improvements in Ring Travelers, of which the following is a specification.

This invention relates to improvements 10 in the construction of travelers used in connection with rings employed in ring spinning, twisting, doubling and like frames for spinning, twisting, doubling or otherwise dealing with cotton or other fibrous material as is well known and of that type 15 which have open ended forks, a connecting bar between the forks, and yarn guiding means in connection with the bar.

The object of the invention is to produce 20 travelers better adapted to control the yarn or thread passing from the delivery rollers to the spindle, that is in a more efficient manner than has heretofore been the case.

I use a traveler having suitable prongs 25 or open ended forks and these are connected by a cross-bar or cross-piece which is substantially horizontal, and, with such substantially horizontal cross-bar or cross-piece I combine winding hooks the arms of which 30 are substantially horizontal and substantially parallel to the horizontal cross bar and are fenced by it so that such winding hook or hooks cannot catch or lock with the spindle or the yarn on same.

35 In order to allow of the use of a fair sized ring and the improved traveler, on frames with a ring rail of narrow width, I provide a split support or socket which fits the rail and serves to receive and support 40 the removable ring, the socket and ring forming a more or less enclosed race for the lower prongs or horns of the traveler. The ring can in such case be readily changed, the socket not requiring to be 45 changed.

The attached drawing illustrates my improvements.

In the said drawing:

Fig. 1 shows the improved traveler in side 50 view.

Fig. 2 is a plan of the traveler and a known form of ring.

Fig. 3 shows a modification in the shape of traveler.

55 I employ a traveler *a* which is fashioned

from thin steel and has open ended forks at each end to engage the ring *b*. In the drawing, straight forks *a'* are indicated which rest on or engage the ring *b* in known manner. These open ended forks are connected together by a cross-bar or cross-piece *a''* which is substantially horizontal so that the uniform level across the top of the traveler is not broken and no proud or projecting portion exists. Combined with such cross-bar or cross-piece *a''* are the yarn guiding or winding hook or hooks. These are shown as pendant from said cross-bar or cross-piece in Fig. 1, and are marked *a³*. They project towards each other and are 70 shown horizontally disposed, being situated equidistant between the forked extremities. The horizontal disposition is extremely effective, as it ensures compactness for the cross-bar or cross-piece and the hooks, and 75 causes the cross-bar or cross-piece *a''* to act as a guard or fence to the hooks.

In Fig. 3 the cross-bar or cross-piece *a''* connecting the forked extremities *a'* is at a lower level than in Fig. 1, and, the hooks 80 *a³* are disposed above and give a practically horizontal continuity to the upper edge of the traveler.

By the above construction I produce a traveler entirely without proud or protruding hooks across the length, the only gap being a very slight space between the hooks *a³* *a³*, and consequently a traveler without any part capable of catching on or locking with the spindle or the yarn of the cop during rotation, even when spinning at the nose 90 part of the cop.

Owing to the use of obtruding or non-guarded hooks this tendency to catch has been a common fault in travelers of the type 95 used prior to our invention.

The constructions indicated, allow of a stronger and heavier traveler being used in the production of finer, softer, and more delicate yarn, and also permit of a greater 100 speed being attained and of a greater length being wound due to the fact that no matter what the speed may be the traveler does not catch the yarn, this being so irrespective of the way the yarn is threaded, or of the direction in which the spindle is rotating.

Viewed in plan, the travelers are curved as to the centre portion, as is usual in travelers of this class, to fit and work against the annular inner wall of the ring, see Fig. 2. 110

In use, the yarn passes from the rollers to the spindle through the forked portion of the traveler at either end as the case may be, then to the yarn guiding or winding hook, 5 and thence to the spindle.

The traveler is caused to assume its proper position on the winding side of the spindle during spinning either twist or weft way according to the direction of rotation of the 10 spindle and at the same time the yarn passes freely on to the spindle when spinning is taking place even at the nose of the cop.

The improved travelers can be used in ring frames using bobbins or tubes or other 15 package carriers.

I declare that what I claim is:

1. A traveler for use in ring spinning, and like frames, comprising a member having forked extremities adapted to engage a

ring, a substantially horizontal cross bar 20 connecting the forked extremities, and hooks on the cross bar intermediate of the forked extremities, said hooks being substantially parallel to said cross-bar, a gap being formed between said hooks.

2. A traveler for use in ring spinning, and like frames, comprising a member having forked extremities adapted to fit a ring, a connection between the forked extremities at each end, a horizontal cross-bar connecting said forked extremities, hooks carried from and parallel with the cross-bar, a gap being formed intermediate of said hooks and a slot intermediate of the cross-bar and 30 hooks.

In testimony whereof I have signed my name to this specification.

JOHN HARGREAVES.
